TONE CONTROL KEY PANEL FOR ACCORDIONS

Aldo Logli, Detroit, Mich.

Application January 25, 1951, Serial No. 13,949

Term of patent 14 years

(Cl. D56—1)

To all whom it may concern:

Be it known that I, Aldo Logli, a citizen of the United States, residing at Detroit, in the county of Wayne and State of Michigan, have invented a new, original, and ornamental Design for a Tone Control Key Panel for Accordions, of which the following is a specification, reference being had to the accompanying drawing, forming a part thereof.

In the drawing:

Figure 1 is a top plan view of a tone control key panel for accordions, showing my design;

Figure 2 is a side elevation of the tone control key panel for accordions; and

Figure 3 is a cross-section taken along the line 3—3 of Figure 1, of the tone control key panel for accordions.

The dotted line showing in the several drawing figures is for illustrative purposes only.

I claim:

The ornamental design for a tone control key panel for accordions, as shown and described.

ALDO LOGLI.
